UNITED STATES PATENT OFFICE.

MICHAL DEMKO, OF CONSHOHOCKEN, PENNSYLVANIA.

FLYCATCHER.

1,371,870.

Specification of Letters Patent. Patented Mar. 15, 1921.

Application filed August 6, 1920. Serial No. 401,627.

To all whom it may concern:

Be it known that I, MICHAL DEMKO, a citizen of Ukraine, residing at Conshohocken, in the county of Montgomery and 5 State of Pennsylvania, have invented certain new and useful Improvements in Fly-catchers, of which the following is a specification.

This invention relates to certain new and 10 useful improvements in fly catchers and has for its primary object to provide a fly catcher in the form of a glass or other transparent cup having a funnel-shaped cover constituting an entrance to the cup for the 15 flies with a normally open outlet adjacent the upper end of the cup body.

A further object of the invention resides in the provision of a fly catcher in the form of a glass receptacle or cup wherein the 20 removable funnel-shaped cover constituting the entrance to the cup for the flies is provided with a plurality of depending concentric ribs, the continuity of which is varied by sections of increased area and 25 reversely curved parts to create many different reflecting surfaces to assist in the retention of the trapped flies within the receptacle.

With the above general objects in view 30 and others that will appear as the nature of the invention is better understood, the same consists in the novel form, combination and arrangement of parts hereinafter more fully described, shown in the accompanying drawing and claimed.

In the drawing, wherein like reference characters indicate corresponding parts throughout the several views,

Figure 1 is a vertical sectional view of a 40 fly catcher constructed in accordance with the present invention showing the removable screw funnel-shaped cover with the depending annular ribs carried thereby, and

Fig. 2 is a horizontal sectional view taken 45 on line II—II of Fig. 1 showing the various shapes and curvatures of the ribs and receptacle wall.

Referring more in detail to the accompanying drawing there is illustrated a fly 50 catcher embodying a cup-shaped receptacle including a flat bottom 3 and a perpendicular side wall 4 carrying a lifting handle 5 by which the receptacle is transported. The receptacle is open at its upper end and is 55 provided with internal threads 6 for the threaded reception of a cover to be presently

described. A constantly open outlet nozzle 7 is formed at the upper end of the side wall 4 diametrically opposite the handle 5 as illustrated in Fig. 2 whereby the contents 60 of the receptacle may be removed therefrom through said nozzle while the cover remains in position thereon.

The type of cover employed herein embodies a funnel-shaped wall 8 having a 65 lower central reduced open end 9 in proximity of the bottom wall 3, the upper end of the funnel-shaped cover 8 having a lateral annular flange 10 positioned above the upper edge of the side wall 4 and resting on 70 the gasket 11, the cover 8 adjacent the flange 10 being provided with a depending portion 12 of increased cross sectional area and externally threaded as at 13 for threading engagement with the threads 6 in the upper 75 end of the side walls 4 of the cup. A plurality of concentric circular walls depend from the funnel-shaped cover 8 and are designated by the reference numerals 14, 15 and 16, the wall 14 being of like cross sectional area over the entire surface thereof. For purposes of confusing paths of travel 80 of the trapped insect, the walls 15 and 16, and the inner faces of the side walls 4 are of various cross sectional areas and 85 reversely curved, the wall 15 being provided with spaced sections 15' of increased cross sectional area while the wall 16 is reversely curved as at 16' at points adjacent the enlargements 15' while the walls 4 are of increased cross sectional area as indicated at 90 14' at points adjacent the reversely curved parts 16', providing reduced passageways between the respective walls depending from the cover section and the side walls of the 95 receptacle.

The quantity of fluid indicated by the reference character *a* is placed within the receptacle with the upper level thereof adjacent the lower edges of the depending 100 walls 14, 15 and 16 and the lower end 9 of the funnel cover 8. The fluid contents of the receptacle are prevented from escaping through the screw connection between the receptacle and cover by the gasket 11 extending 105 between the cover flange 10 and the upper edge of the receptacle. Insects, such as flies, entering the funnel 8 will move downwardly through the entrance opening 9 into the receptacle and in attempting to 110 escape will pass upwardly between the walls 14, 15 and 16 and will contact the

walls 14', 15' and 16' at the restricted passageways between the respective walls and upon dropping downwardly, the trapped insects will fall into the body of fluid and be retained within the receptacle. When it is desired to empty the contents of the receptacle it is unnecessary to remove the cover as the outlet spout is provided for this purpose, the fluid and insects trapped 10 within the receptacle escaping through the outlet nozzle. For purposes of cleaning the receptacle, the cover is unscrewed therefrom and the faces of the several walls depending from the cover may be cleaned and the receptacle placed in a perfectly sanitary condition.

While there is herein shown and described the preferred embodiment of the present invention, it is nevertheless to be understood that minor changes may be made therein without departing from the spirit and scope of the invention as claimed.

What I claim as new is:—

1. A fly catcher of the type described comprising a receptacle having internal screw threads at the upper end thereof, a funnel-shaped cover having an externally threaded depending shoulder portion screwed into the upper end of the receptacle, and a plurality of concentric walls depending from the funnel-shaped cover.

2. A fly catcher of the type described comprising a receptacle having internal screw threads at the upper end thereof, a funnel-

shaped cover having an externally threaded 35 depending shoulder portion screwed into the upper end of the receptacle, and a plurality of concentric walls depending from the funnel-shaped cover, some of said walls having spaced sections of increased cross 40 sectional area and others of said walls having spaced reversely curved sections.

3. A fly catcher of the type described comprising a receptacle having internal screw 45 threads at the upper end thereof, a funnel-shaped cover having an externally threaded depending shoulder portion screwed into the upper end of the receptacle, a plurality of concentric walls depending from the funnel-shaped cover, and an outlet spout formed 50 in the receptacle adjacent the upper end thereof.

4. A fly catcher of the type described comprising a receptacle, a funnel-shaped cover removably supported thereon and having 55 the lower end thereof constituting a reduced opening to the receptacle, and a plurality of concentric walls depending from said funnel-shaped cover with the lower ends thereof lying in the same plane as the entrance 50 opening to the receptacle.

In testimony whereof I affix my signature in presence of two witnesses.

MICHAL DEMKO.
